UNITED STATES PATENT OFFICE.

XAVIER SEITZ, OF EMMISHOFEN, SWITZERLAND.

FOLDING HOOD FOR CARRIAGE BODIES.

Application filed April 23, 1927, Serial No. 186,134, and in Switzerland April 28, 1926.

The invention relates to the superstructure of a motor propelled vehicle and more especially to the construction of a sheet van body with a waterproof cover.

5 The main object of the invention is to provide a simple and efficient construction of the hoops supporting the waterproof sheet. A further object of the invention consists in the provision of improved means 10 to guide the hoops along the supporting rails in such a manner that the hoops are running smoothly in their guides with little friction and with no play.

I attain these and other objects of my invention by the means disclosed in the accompanying drawings, in which

Fig. 1 is a side view of a motor propelled vehicle fitted with the improved folding hood.

20 Fig. 2 is a top view of the same.

Fig. 3 is a side elevation of the end part of a top rib,

Figs. 4 and 5 show in a side view and in a top view a guide member of a top rib.

25 Fig. 6 shows in a side view a center piece of a top rib.

Fig. 7 is a cross section taken on line A—A of Fig. 6.

The new device comprises vertical trusses 30 *b* which are fixed to the two opposite side walls *a* of the carriage body. A longitudinal rail *c* is placed on top of the trusses *b* arranged on each side wall *a* of the body. The rail *c* with the pillars *b* form part of a frame for

35 the drop windows *d*, which windows are slidably mounted in said frame. On each longitudinal rail *c* a top guide rail *e* of U-shaped cross section is placed. The upper ends *f* of the vertical members of said rail *e* are bent inwardly. Carriages *h*, each fitted 40 with two rollers *g* are mounted to run freely in the channel formed in the top guide rails *e*. All the carriages *h*, running on the same rail *c*, are interconnected by an endless rope *k*, which passes over two guide rollers *i*, rotatably mounted on a side wall *a* near the front and rear ends thereof. A chain may 45 be used instead of the rope. Each carriage *h* is rotatably mounted in the downwardly

50 projecting end of a hoop *l*. For this purpose each carriage *h* is provided with a bolt *m*, which is screwed into a sleeve *n*. The sleeve *n* engages a bore of the end portion 55 of a hoop *l*. The carriages *h* therefor are arranged to run freely on the rails *e* and no jamming of the same will occur, when the

carriages *h* are moved. The waterproof sheet *o* is supported on the hoops *l* and is spread or folded according to the direction in which the carriages *h* and, therewith, the 60 hoops *l*, are moved. The bolt *m* facilitates the fitting of the carriages *h* to the hoops *l*. By screwing the bolt *m* more or less into the sleeve the distance of the hoops *l* from the top guide rails *e* may be varied. Therefore 65 the roof can be moved with little friction and at the same time the hoops *l* remain in firm connection with the rails *e*. Each hoop *l* rests on spring *p* placed around the bolts *m*, which springs *p* absorb the shocks and 70 prevent the rattling when the car is running over rough roads. Two rollers *r*, which are mounted on a bolt *q* press against the edges *f* of the rails *e*. The bolt *q* is slidably arranged in a vertical slot *s* of the carriage *h* 75 and rests on two blade springs *t*, fitted on the bolts *u* of the rollers *g*. The rollers *r*, which are pressed against the edges *f* of the rails *e* by the springs *t*, assures a quiet, noiseless running of the carriage *h* on the rails *e*. 80

The hoops *l* can be moved on the rails *e* to the rear part of the car together with the folded cover *o* and the carriages *h* run into the downwardly projecting portion *e'* of the rails *e*. The hoops *l* are moved either by the 85 rope or chain drives *k*, by means of a crank; or by hand. Each hoop stick *l* comprises two hollow rods of elliptical cross section. Into the two rods projects a bar *v*. The bar *v* is riveted to the one hollow rod and is 90 slidable in the other rod. To the bar *v* two flat springs *w* are fixed which effect a sliding but tight fit of the rail *v* in the hollow rod. The use of such adjustable top ribs *l* 95 is suitable, especially for carriage bodies, of varying breadth from the rear to the front. The carriage *h* could be mounted on the hoop *l* by means of bolts without the sleeves without affecting the function of the springs *p* which operate to prevent rattling in the 100 threaded connections between the bolts *m* and the hoops *l*.

What I claim and wish to secure by U. S. Letters Patent is:—

1. A folding hood for carriage-bodies comprising in combination a cover sheet, hoops supporting said sheet, carriages on said hoops, each carriage being provided with a screw-threaded bolt, a sleeve screwed on said bolt, said hoops having bores in their ends in which said sleeves are mounted and a rail to form a race for said carriage. 105 110

2. A folding hood for carriage-bodies comprising in combination a cover sheet, hoops supporting said sheet, carriages on said hoops, each carriage being provided with a bolt and a sleeve screwed on said bolt, said hoops having bores in which said sleeve is mounted, springs between said carriages and the ends of said hoops and a rail to guide said carriages.
- 10 3. A folding hood for carriage-bodies comprising in combination a cover sheet, hoops supporting said sheet, carriages on

said hoops, each carriage being provided with a bolt connecting said carriage to one of said hoops and a spring on said bolt and between the carriage and the end of the hoop to which said carriage is connected and a channel rail to guide said carriages, said carriages having elastically mounted guide rollers operating in the channel of said rail.

In witness whereof I affix my signature.

XAVER SEITZ.
